US00D862017S

(12) **United States Design Patent** (10) **Patent No.:** **US D862,017 S**
Dou et al. (45) **Date of Patent:** **** Oct. 1, 2019**

(54) **FILTER FOR A ROBOTIC VACUUM**

(71) Applicant: **BEIJING XIAOMI MOBILE SOFTWARE CO., LTD.**, Haidian District, Beijing (CN)

(72) Inventors: **Wenbo Dou**, Beijing (CN); **Ningning Li**, Beijing (CN)

(73) Assignee: **Beijing Xiaomi Mobile Software Co., Ltd.**, Beijing (CN)

(**) Term: **15 Years**

(21) Appl. No.: **29/615,911**

(22) Filed: **Aug. 31, 2017**

(51) **LOC (12) Cl.** **15-05**

(52) **U.S. Cl.**

(57) **CLAIM**

The ornamental design for a filter for a robotic vacuum, as shown and described.

DESCRIPTION

FIG. 1 is a front view of a filter for a robotic vacuum of the new design;

FIG. 2 is a back view of the filter for a robotic vacuum;

FIG. 3 is a left view of the filter for a robotic vacuum;

FIG. 4 is a right view of the filter for a robotic vacuum;

FIG. 5 is a top view of the filter for a robotic vacuum;

FIG. 6 is a bottom view of the filter for a robotic vacuum;

FIG. 7 is a perspective view of the filter for a robotic vacuum; and,

FIG. 8 is another perspective view of the filter for a robotic vacuum.

1 Claim, 8 Drawing Sheets
